Primary Examiner — Ricky Pham(74) *Attorney, Agent, or Firm* — Alleman Hall McCoy
Russell & Tuttle LLP(57) **CLAIM**

The ornamental design for a kitchen drawer accessory, as shown and described.

DESCRIPTION

FIG. 1 is a top perspective view of a design for a kitchen drawer accessory according to a first embodiment of the present disclosure.

FIG. 2 is a cross-sectional view taken along line 2-2 of FIG. 1. FIG. 3 is a second top perspective view of a kitchen drawer accessory according to a second embodiment of the present disclosure.

FIG. 4 is a cross-sectional view taken along line 4-4 of FIG. 3. FIG. 5 is a third top perspective view of a kitchen drawer accessory according to a third embodiment of the present disclosure; and,

FIG. 6 is a cross-sectional view taken along line 6-6 of FIG. 5. The solid lines in FIGS. 1-6 illustrate a kitchen drawer accessory according to the present disclosure. The broken lines form no part of the claimed design. Top, bottom, and left views are not shown as they do not show any additional claimed features.
